(57) CLAIM

The ornamental design for a playing surface for spinning top toy as shown and described.

DESCRIPTION

FIG. 1 is a front elevational view of a playing surface for spinning top toy, showing the new design;

FIG. 2 is a rear elevational view thereof;

FIG. 3 is a left-side elevational view thereof;

FIG. 4 is a right-side elevational view thereof;

FIG. 5 is a top plan view thereof;

FIG. 6 is a bottom plan view thereof;

FIG. 7 is a front, right-side, top perspective view thereof;

FIG. 8 is a rear, left-side, bottom perspective view thereof;

FIG. 9 is a front, right-side, top disassembled perspective view, showing a state of being separated into four fasteners, a cover, a base, and four legs;

FIG. 10 is rear, left-side, bottom disassembled perspective view, showing a state of being separated into the four fasteners, the cover, the base, and the four legs;

FIG. 11 is a cross-sectional view taken along line 11-11 in FIG. 1;

FIG. 12 is a cross-sectional view taken along line 12-12 in FIG. 5;

FIG. 13 is a perspective view of one of the fasteners;

FIG. 14 is another perspective view of the fastener shown in FIG. 13;

FIG. 15 is a perspective view of one of the legs; and,

FIG. 16 is another perspective view of the leg shown in FIG. 15.
